FACE GUARD FOR SEWING MACHINE
OPERATORS

Jonas F. Imberman, Los Angeles, Calif.

Application April 7, 1943, Serial No. 482,197

7 Claims. (Cl. 112—261)

This invention relates to a guard for safely protecting the face of the operator from being injured by broken needles.

In operating sewing machines, especially wherein the operation of bar tacking, sewing on buttons and snaps is concerned, it is not infrequent that, due to the heat generated in the needle through fast stitching operations, the temper of the needle is reduced causing the point to bend and consequently the needle to break, sometimes into several pieces above the detempered areas and strike the operator in the face. Sometimes this defect resides in the improper spacing apart of the perforations in the buttons or in the button clamp springs which become worn and then permit the buttons to move relatively to said clamp spring causing the needles to strike the buttons and break. Furthermore, fear of being injured by fragments of broken needles thrown from the machine, heretofore set up in the mind of the operator, has reduced efficiency and, owing to the numerous casualties to be insured against, a high rate of insurance has been required.

It is among the major objects of this invention to provide for the elimination of such accidents, lower costs of present high insurance rates, and foster in the mind of the operator freedom from fear of injury, thereby increasing the efficiency of the operator and augmenting the output produced thereby.

It is also among the objects of the invention to provide, as a new article of manufacture, a superior combined hanger and transparent guard plate adjustably mountable upon a standard make of sewing machine to protect the face and neck, and more particularly the eyes of the operator against being injured by fragments of broken needles thrown from the machine.

The invention provides a one-piece hanger for supporting the transparent guard plate, thereby simplifying structures known to the prior art.

Other objects, advantages and features of invention will hereinafter appear.

Referring to the drawing, which illustrates what is at present deemed to be a preferred embodiment of the invention, said drawing is a perspective view of the device in its mounted position in relation to a sewing machine of the Singer type, a sufficient portion of said sewing machine being included in the view to illustrate the relation of the invention thereto.

Referring in detail to the drawing, the main parts of the face-protecting attachment 1 there-

in shown are the vertical hanger strip 2 consisting of a rigid sheet material and furnished at its lower end with a broadened foot portion 3 having a downwardly inclined body portion 4 which is bifurcated so as to provide the two spaced apart side arms 5. To the lower face of this bifurcated member is shown secured, by means of screws 6, the transparent guards plate 7. However, it is optional whether said guard plate is secured to the bifurcated member in an underlying or an overlying relation, either positioning thereof coming within the scope of the claimed invention.

In the illustrated embodiment of the invention said guard plate is made of a transparent material, for example some plastic substance, and the screw holes therethrough to be threaded to have the screws screwed into them. If a glass guard plate is used some other conventional attaching means will be provided therefor. In either case a shatter-proof transparent material should be used.

As viewed in the drawing the upper part of the mounted hanger strip 2 is widened by providing it with a leftward extension 8 thus affording room for cutting downwardly into the upper end of the strip a slot 9 which is in substantial alinement with the left edge of the body portion of said strip 2. It is deemed best to make the slot 9 open at its upper end, as otherwise the screw 10, shown extending therethrough would have to be completely unscrewed before its threaded portion could be passed through the slot. Said screw is the conventional screw whereby the usual face plate is attached to the underlying portion of the sewing machine head 12, said screw in order to provide room for the thickness of the slotted portion of the plate under its head, having been out-screwed a short distance, and then being screwed down to cause its head to clamp the plate in its proper position of vertical adjustment.

From that edge of the strip 2 which is opposite to its slotted part, a little lower down, projects a guide arm 15 to the outer part of which is fixed, and from which rearwardly projects a stud 16 which enters a hole 11a through the face plate 17. Said hole is vertically elongated and hence permits the desired amount of vertical adjustment of the attachment 1, but the stud has a working fit in relation to the width of the hole and therefore stabilizes the attachment against lateral displacement.

The guide arm 15 is shown bent at 20 in order to contour it to the arcuate part of the conventional face plate shown, and the terminal part of

said arm is rebent to extend laterally in a flatwise contact with the flat wing portion 21 of the face plate 17, the flat forward surface of said face plate and the face of said wing thereof being laterally spaced apart horizontally and united by means of the arcuate part of the face plate to which conforms the bent part 20 of the arm 15. Also, when the device is in its mounted position the entire straight portion of the strip 2 has a direct flatwise contact with the outer surface of the face plate 17, the flatwise contacts which have been described contributing to the secure, satisfactory manner in which the whole device is kept immovable in its mounted position by the screwed down clamping screw 10. As a further advantageous result, no objectionable open space through which needle fragments might pass is produced between the front surface of the face plate 17 and the lower part of the mounted strip 2.

Owing to the foot portion 3 of the hanger being formed as an edgewise expansion of the strip 2 this expanded part functions as an auxiliary shield which cooperates with the transparent plate 7 to prevent broken needle fragments from being thrown toward the operator's face.

In the drawing is shown the conventional clamp spring 25 which holds buttons and other articles in place while being sewed on and automatically moves them about as required to bring their apertures into the path of the needle during this operation. Also the point portion of a needle is shown, it being understood that said needle is carried in the usual manner by the needle holding rod 27 a portion of which projects upwardly beyond the face plate 17. The feed plate 28 rests upon the throat plate 28a which, in turn rests upon the bed 29 of the machine.

As the transparent guard plate 7 is at all times located only a short distance above the articles which are being sewed on, the amount of vertical adjustment of which the device is capable, though not extensive, is amply sufficient to vary the position of said transparent plate to the extent required to accommodate its position to the eyes of different operators who, owing to differences in stature, vary somewhat as to height above the work.

What is claimed is:

1. A device of the kind described comprising an article of manufacture consisting of a strip of substantially rigid sheet material carrying at one end a transparent guard plate and having a longitudinally extending slot in its opposite end portion to receive the stem of a screw for clamping the device to the face plate of a sewing machine in a vertically adjustable manner, said strip having a stabilizing arm which projects from one of its sides and which carries a stud insertable into a recess or hole in the face plate

of a sewing machine to stabilize the attached device.

2. The subject matter of claim 1 and, said guard plate extending obliquely downward and forward when said strip is in its upstanding mounted position.

3. The subject matter of claim 1, and said slot having an open upper end the width of said slot being less than the diameter of the head of the attaching screw.

4. The combination, with the upstanding face plate of a sewing machine; of a hanger strip having through it a vertical slot with an open upper end, a screw passing through said slot and clamping said strip to said face plate in a vertically adjustable manner, and a transparent needle guard plate carried by the lower portion of said strip, said guard plate extending obliquely downward and forward when said strip is in its upstanding mounted position.

5. The combination, with the attached upstanding face plate of a sewing machine, said face plate having a flat front face portion, a backwardly spaced flat face portion, and an arcuate portion joining said two face portions; of a hanger including a strip of substantially straight flat rigid sheet material, means whereby said strip is secured to said face plate in a vertically adjustable manner and in an upstanding position wherein the strip engages said front face portion of said face plate with a flatwise contact, said strip having a laterally extending stabilizing arm which is contoured to fit over the aforesaid arcuate portion of said face plate, said arm having a terminal flat portion which contacts in a flatwise manner with the aforesaid backwardly spaced flat portion of said face plate, and a stabilizing connection between said last recited part of said face plate.

6. The subject matter of claim 5 and, said stabilizing connection consisting of a stud carried by said arm and projecting into a recess in said face plate.

7. The combination, with the upstanding face plate of a sewing machine; of a hanger strip having through it a vertical slot, and a screw passing through said slot and securing said hanger strip to said face plate in an overlying vertically adjustable manner, a transparent guard plate carried by the lower portion of said hanger strip, said guard plate extending obliquely downward and forward when said strip is in its upstanding mounted position, said hanger strip having a lower portion which is expanded in an edgewise manner and which forms an auxiliary guard which cooperates with the transparent plate to prevent fragments of broken needles from being thrown toward the face of the operator.
